UNITED STATES PATENT OFFICE.

JAMES H. RAND, OF NORTH TONAWANDA, NEW YORK.

INDEX.

Application filed February 18, 1921. Serial No. 445,953.

To all whom it may concern:

Be it known that I, JAMES H. RAND, citizen of the United States of America, and resident of North Tonawanda, in the county of Niagara and State of New York, have invented new and useful Improvements in Indexes, of which the following is a specification.

This invention relates to indexes of the so-called visible index type adapted to display removable and interchangeable index strips containing lists of names or similar matter arranged in some orderly or arbitrary sequence. Heretofore index devices of this character have consisted essentially in panels or frames on the face of which are mounted a series of index strips arranged edge to edge. An example of indexes of this character is to be found in Letters Patent of the United States No. 1,025,997, granted to me May 14, 1912. In this kind of index the capacity of each panel or frame is strictly limited by its area, and where the list of names, or other subject-matter of the index, requires a very large number of index strips, the number running into the hundreds of thousands in some large mercantile establishments, it will be apparent that an index equipment of the kind heretofore used, having sufficient capacity, becomes exceedingly bulky, costly and cumbersome to manipulate.

A principal object of the present invention is greatly to increase the capacity of each index panel or frame without increasing its size, thus reducing the bulk and cost of an installation, and rendering it more convenient to use by concentrating or centralizing a greater number of names or other items in smaller compass.

This I accomplish by mounting in each main panel or frame a plurality of overlapping, hinged, subsidiary frames or holders, each carrying a series of the individual index strips. Each subsidiary frame or holder occupies only the space in the main frame or panel which has heretofore been occupied by an individual index strip, and consequently the capacity of the device as a whole is multiplied by the number of individual index strips carried by each holder. For example a panel which has heretofore held 200 index strips will hold 200 subsidiary frames or holders, and if each holder accommodates 50 index strips the capacity of the index containing the present invention will be 10,000

index strips instead of 200. In practice the increase of capacity may be made even greater by increasing the number of index strips on each subsidiary frame or holder. 60

Another feature of the invention is its self-indexing capacity by which the exposed marginal index element on each holder becomes an index guide to subject-matter falling in sequence between each exposed index element and the next adjacent exposed index element. 65

Other features will hereinafter be described and particularly pointed out in the claims. 70

In the accompanying drawings which illustrate certain embodiments of the invention,—

Figure 1 is a front elevation of a part of the index containing a number of holders 75 and illustrating their relation when in use in a main supporting frame;

Figure 2 is a side or edge view of the parts shown in Fig. 1;

Figure 3 is a rear elevation of one of the 80 individual holders;

Figure 4 is an enlarged, cross sectional, detail view on line 4—4 of Fig. 3, the parts being shown of exaggerated thickness for the sake of clearness; 85

Figure 5 is a similar enlarged, cross sectional detail view on line 5—5 of Fig. 3;

Figure 6 is a front elevation of an individual holder containing certain modifications; 90

Figure 7 is an enlarged sectional view on line 7—7 of Fig. 6, partly broken away;

Figure 8 is a similar view to Fig. 7, showing a further modification; and

Figure 9 is an isometric view of one form 95 of shield, presently to be described.

The holders for the index strips are mounted in a frame of the type having opposed inwardly facing channels to retain the ends of supports on which the holders are hinged. The flanges of the main frame forming the channels, indicated fragmentarily by dotted lines, may be of any usual or preferred form. Such frames are usually made of sheet metal with their lateral 100 margins bent inwardly to provide inwardly extending flanges 10, 10, forming channels with the frame back; but the particular construction of the main frame is not important so far as the present invention is 105 concerned.

Each holder is hinged to a support hav-

ing laterally projecting ends which are engaged by the flanges 10 of the main frame. As shown in Figs. 1, 2 and 3 these supports consist of bars or strips of Bristol board 11. The particular form of support, however, is not essential to this invention, and it may be of any suitable material instead of Bristol board or cardboard, as metal or sheet celluloid, and may 10 be of any usual or preferred form. For example, I have illustrated in Figs. 6, 7 and 8 a form of support 11^a consisting of heavy paper, sheet celluloid or other suitable sheet material having bent-over lips 12 which engage and retain a bent-over margin 13 of the card or holder body.

Each holder comprises a card or sheet 14, which constitutes the holder body, attached to its support 11, as by staples 15, 20 15, Figs. 1 and 3, and creased along a line 16 which constitutes a hinge on which the holder swings. The attachment of the card to the support in Figs. 6, 7 and 8 is by means of the folded margin 13. Any suitable form of attachment, and any suitable 25 form of hinge connection may be employed. The structures thus far described may all be of constructions well known in visible indexes, and in and of themselves constitute 30 no part of the present invention.

Each holder has attached to its side edges, and preferably both on the front and back of the holder, an inwardly extending flange or lip to engage the ends of the indicator 35 strips 17. In the form illustrated in Figs. 1, 3 and 5 these lips are made of suitable resilient sheet material, preferably sheet celluloid, folded around the edge of the holder body to form a front lip 18 and a 40 rear lip 19. Each lip is preferably formed with a rounded, inturned edge or bead 20 to afford a smooth and easy entrance for the ends of the index strips 17, and to provide a handsome and finished appearance. 45 The lip structures are held in place on the edge of the holder body 14 by a fold or bent-over margin 21 on the latter, which engages the bend of the bead 20 of one of the lips (see Fig. 5) thus securing the 50 entire lip structure to the holder body. The lip structure is applied by slipping it endwise on the folded margin 21. Obviously the folded margin 21 instead of being integral with the body or card 14 55 could be made of a strip of sheet material cemented or otherwise secured to the margin of the card.

The free horizontal edge of each holder is also provided with a pocket or sheath of 60 transparent material preferably on each side of the holder, similarly formed of sheet celluloid or other transparent, resilient, sheet material, to provide a front lip 22 and a rear lip 23, Fig. 4, each having an inwardly folded or beaded edge 24, similar

to 20 in Fig. 5. This lip structure is held in position on the holder body 14 by a fold or bent-over margin 25 in substantially the same way as the side lip structures. In assembling the parts the side lip structures are 70 first slipped on to the folds 21, and the free edge lip structure is then slipped on to the fold 25 thereby locking the side lip structures in place.

The index strips 17, which may bear 75 names in alphabetical order, or other inscriptions arranged in predetermined sequence according to the subject matter of the index, are held at their ends by the side flanges or lips, which are made of resilient 80 material and are so formed as to exert a pinch on the ends of the index strips, preventing them from overriding one another, or from becoming dislodged or closing together, even if one or more of the strips 85 be removed thereby leaving spaces or gaps. The resilient lips moreover, make it possible to use index strips of very light and flexible material such as thin paper without danger of their becoming disarranged. If 90 non-resilient lips are used, the index strips must be sufficiently thick and stiff so that they will support one another edge to edge.

The last or endmost index strip 17^a on each side of the holder is inserted in the 95 sheath formed by the lip 22 or 23. These endmost index strips will always be exposed to view through the transparent lips, either on the obverse side of the holders as 100 illustrated at the bottom of Fig. 1 when the holders hang downward in normal position, or on the reverse side of the holder when the latter are swung upward on their hinges as illustrated at the top of Fig. 1, 105 since the holders are mounted in the main frame in overlapped, spaced relation by the supports 11.

In order to have the index strips in normal position, right-side up to the view of the user, the strips on the obverse sides of the holders will be arranged in sequence from the hinged edge toward the free edge of the holder, while the strips on the reverse sides of the holders will be upside down and arranged in sequence from the free edge toward the hinged edge of the holder. Thus when a holder is swung upward to expose its reverse side, the index 115 elements will appear right-side up and in orderly sequence.

To facilitate inspection of the index and to prevent injuring, disarranging or soiling the index strips by running a finger or pointer over them, a cover or shield is provided, consisting of a strip 26 overlying the 120 whole series of index slips. The shield is preferably made of transparent sheet material such as celluloid, so that the inscriptions on the index slip may be read through it. It may be of any desired width, and 125

placed in any desired lateral position. Thus in Figs. 1 and 3 it is shown at the middle of the holder, while in Fig. 6 it is shown at one side covering the column of names 5 along which a user might naturally run the index finger to locate the desired name. The shield 26 may be variously held in position. It may be made with an upturned lip 27 which engages the fold 24, as illustrated in 10 Fig. 4 or Fig. 8, thus locking it in place. To insert the shield of this construction it is merely pushed down into the pocket formed by lip 22 or 23 until the lip 27 snaps under lip 24; it is removed by sliding 15 it endwise of lip 22 or 23. Or, it may be made with a straight unfolded edge at each end (see Figs. 6 and 7) one end being tucked into the pocket at the free edge of the holder and the other end being held by a tongue 20 28 formed on the holder body 14. The shields 26 moreover help to hold the index slips flat and in place.

Some of the differences between the modifications shown in Figs. 6 to 8 and the form 25 shown in the other figures, have already been described. The principal additional difference consists in the fact that provision is made for applying the index strips to only one side of the holders instead of both 30 sides. Retaining lips or flanges are therefore provided only on one side of the holder body 14. Such lips, as herein shown, consist of folded pieces of sheet celluloid comprising a rear flap 29, which may be attached by a piece of gummed fabric 30, or by cement or in any other suitable way, to 35 the margin of the card or holder body 14, and a front flange or lip 31. The side flanges may be similarly formed and attached. The general purpose and mode of 40 use of these modifications is the same as that of the form shown in Figs. 1 to 5, but the index will have only half the capacity of the other form as only one side of each 45 holder is utilized for the index slips.

From the foregoing description it will be seen that the main frame 10 carries a series of removable and interchangeable subsidiary frames in the form of holders, the several subsidiary frames being mounted one above another in overlapped spaced relation with their free margins projecting one beyond another, each being hinged to its support. As many subsidiary frames or 50 holders may be used as desired, the number being limited only by the length of the main frame. Each subsidiary frame or holder in turn carries a series of removable, interchangeable and individual index strips on one or both sides of the holder, the endmost index strip on each holder, that is, the one on the free projecting margin, being exposed to view. The index strips are arranged in alphabetical order, or it may be numerically or accord-

ing to any other arbitrary sequence according to the classification or plan adopted for the particular index, the sequence running continuously from one holder to the next. Thus the device is self-indexing, the exposed index element on the projecting margin of each holder constituting an index for the matter between itself and the next exposed index element. No index tabs nor other special indexing contrivances are necessary to guide the user to the desired item. For illustration, referring to Fig. 1, if the user desires to refer to the name "Dudley," or some name alphabetically subsequent to "Dean" but prior to "Emerson," he will 75 swing the holder having "Dean" on its exposed margin upwards thereby disclosing all names between "Dean" and "Emerson." Thus the exposed items of the series, no matter what particular items may appear 80 on the projecting margins of the holders, constitute index guides by which the whole series is subdivided, the series being self-indexing and requiring no extraneous indexing guides. 85

I claim:

1. An index comprising a main frame, a plurality of holders mounted on the main frame in overlapped, spaced relation with their free margins projecting one beyond another, and a series of index elements mounted on each holder, the endmost index element being on the projecting margin of the holder and normally exposed to view. 95

2. An index comprising a main frame, a plurality of holders mounted on the main frame in overlapped, spaced relation with their free margins projecting one beyond another, and a series of index elements mounted on the holders and bearing inscriptions arranged in a predetermined order of sequence throughout the several holders, whereby the exposed index elements on the projecting margins of the holders constitute self-indexing means for the whole series. 100

3. An index comprising a main frame, a plurality of holders mounted on the main frame in overlapped, spaced relation with their free margins projecting one beyond another, and a series of index elements mounted on both sides of the holders and bearing inscriptions arranged in a predetermined order of sequence throughout the several holders, whereby the exposed index elements on the projecting margins of the holders constitute self-indexing means for the whole series. 115

4. An index comprising a main frame, a plurality of holders mounted on the main frame in overlapped, spaced relation with their free margins projecting one beyond another, each holder comprising a body having inwardly extending lips on the side edges of the body, and a sheath of transparent material forming a pocket on 120 125 130

the free projecting margin of the body, a series of index strips held at their ends by said side lips on the several holders, and an index strip in said pocket.

5. An index comprising a main frame, a plurality of holders mounted on the main frame in overlapped, spaced relation with their free margins projecting one beyond another, each holder comprising a body having 10 inwardly extending lips on the side edges of the body and on both obverse and reverse faces thereof, and a sheath of transparent material forming pockets on both obverse and reverse faces of the free margin of the 15 body, said lips and pockets being adapted to hold index strips.

6. A holder for index elements comprising a support, a rectangular body attached at one edge to the support, a fold at each 20 of the other three edges, and a lip structure bent around the edge of each of said three unattached edges to form inwardly extending lips on both sides of the body, one of said lips being inwardly turned and 25 cooperating with the fold on the edge of the body to attach the lip structure to the body.

7. A holder for index elements comprising a support, a rectangular body attached at one edge to the support, a fold at each 30 of the other three edges, and a lip structure bent around the edge of each of said three unattached edges to form inwardly extending lips on both sides of the body, one of said lips being inwardly turned and co-

operating with the fold on the edge of the 35 body to attach the lip structure to the body, the lip structure at the edge opposite the attached edge of the body extending across the ends of the side lip structures and locking them in position.

8. A holder for index strips comprising a body, a plurality of index strips arranged side by side on the body, means to hold said index strips at their ends, a pocket at the free edge of the body, and a protective 45 shield extending across the index strips, one edge of the shield being held in said pocket.

9. A holder for index strips comprising a body, a plurality of index strips arranged side by side on the body, means to hold said 50 index strips at their ends, a pocket at the free edge of the body, and a protective shield extending across the index strips, one edge of the shield being held in said pocket, and means on the body to engage the opposite 55 edge of the shield.

10. A holder for index strips comprising a body, a plurality of index strips arranged side by side on the body, means to hold said 60 index strips at their ends, a pocket at the free edge of the body having an inturned edge, and a protective shield extending across the index strips having a folded edge adapted to engage the inturned edge of the 65 pocket.

Signed by me at North Tonawanda, New York this fourteenth day of February, 1921.

JAMES H. RAND.
